UNITED STATES PATENT OFFICE

MARK M. STONE, OF MALDEN, MASSACHUSETTS, ASSIGNOR TO S. ROBERT STONE, OF WABAN, MASSACHUSETTS

DESIGN FOR A TEXTILE FABRIC

Application filed July 29, 1932. Serial No. 44,483. Term of patent 3½ years.

To all whom it may concern:

Be it known that I, MARK M. STONE, a citizen of the United States of America, residing in Malden, in the county of Middlesex and Commonwealth of Massachusetts, have invented a new, original, and ornamental Design for a Textile Fabric, of which the following is a specification, reference being had to the accompanying drawing, forming part thereof.

The figure is a face view of the fabric.

I claim:

The ornamental design for a textile fabric as shown.

Signed by me at Boston, in the county of Suffolk and Commonwealth of Massachusetts, this 28th day of July 1932.

MARK M. STONE.
